SLIDING BOLT

James A. Karns, 2605 Addyston Road,
Akron, Ohio 44313

Filed Nov. 16, 1964, Ser. No. 82,640

Term of patent 14 years

(Cl. D50—5)

FIG. 1

FIG. 2

FIG. 3

FIG. 4

FIGURE 1 is a view of the front face of the sliding bolt;

FIGURE 2 is an end view of the sliding bolt;

FIGURE 3 is a bottom view of the sliding bolt; and

FIGURE 4 is a view of the back face of the sliding bolt.

The dominant features of the design are shown in full lines. The slide has been shown broken away to show indeterminate length.

I claim:

The ornamental design for a sliding bolt, as shown and described.
